UNITED STATES PATENT OFFICE.

EDWARD J. KOBERT, OF WOODSIDE, NEW YORK.

SHOE-TREE.

1,062,164.

Specification of Letters Patent.

Patented May 20, 1913.

Application filed May 7, 1912. Serial No. 695,593.

To all whom it may concern:

Be it known that I, EDWARD J. KOBERT, a citizen of the United States, and residing at Woodside, in the county of Queens and 5 State of New York, have invented certain new and useful Improvements in Shoe-Trees, of which the following is a specification, such as will enable those skilled in the art to which it appertains to make and use 10 the same.

The object of this invention is to provide a shoe-tree which is simple in construction, and operation, and which may be more easily and conveniently inserted into a shoe 15 and operated, than other devices of this class as usually constructed, and with these and other objects in view the invention consists in a device of the class specified constructed as hereinafter described and 20 claimed.

The invention is fully disclosed in the following specification of which the accompanying drawing forms a part, in which the 25 separate parts of my invention are designated by suitable reference characters in each of the views, and in which:

Figure 1 is a diagrammatic side view of a shoe and showing my improved shoe-tree, part of the construction being in section:- 30 Fig. 2 a plan view of the shoe-tree with a part shown in section, and Fig. 3 a section on the line 3—3 of Fig. 1.

In the practice of my invention I provide a heel block 1, said block being provided 35 with a straight front face 2 and the back and side surfaces thereof being adapted to fit the back and side portions of the heel part of the shoe, and the block 1 is preferably provided in the side and back walls 40 thereof with grooves 3, and is also preferably provided on the bottom thereof with knobs 4, this construction being designed to permit of the circulation of air around and beneath said block when the shoe-tree is in 45 use. The block 1 is also provided centrally of the front face thereof with a recess 5 in which is pivoted a bar 6 composed of two parallel side members 7 separated by blocks 8 at the front and rear ends thereof so as 50 to provide a narrow space 9 between the parallel side members 7.

Connected with the front end of the bar 6 and midway thereof are yoke-shaped hangers 10 and 11 in the bottom portion of which 55 is a sliding bar 12 similar in form to the side members 7 of the bar 6, and the bar 12

is provided in the top thereof with ratchet teeth 13, and I also provide a toe block 14 adapted to fit in the toe portion of the shoe and provided in its rear face with a recess 60 15 in which the front end of the bar 12 is pivoted, as shown at 16, and said toe block is also preferably provided with longitudinal grooves 17 to permit of the free circulation of air in the toe of the shoe when the 65 tree is in use.

Pivoted between the rear end portions of the side members 7 of the bar 6 is a hand lever 18 provided with a handle 19, and the lever 18 is provided, in the construction 70 shown, with forwardly directed jaws 20 between which is pivoted a pawl 21 which operates between the side members 7 of the bar 6 and in the space 9 and in connection with the ratchet teeth 13 in the bar 12. 75 Pivoted to the lever 18 above the pawl 21 is a catch dog 22 the bottom edge of which is provided with teeth 23, and secured to the front of the heel block 1 is a ratchet plate 24 in connection with which the dog 80 22 operates.

The rear end of the bar 12 is provided with a transverse stop pin 25 which bears on the bar 6, and in the operation of this device, it is inserted into the shoe with the 85 bar 12 in its rearmost position. The dog 22 is then raised by means of a handle 26, or in any other way, and the lever 18 is swung forwardly and backwardly. In this manipulation of the lever 18 the pawl 21 operates in connection with the teeth 13 of the bar 12 to force the toe piece 14 into the toe portion of the shoe, and the dog 22 will operate to hold said toe piece in proper position in the shoe. In this operation the shoe 95 may be thoroughly stretched and maintained in proper form any desired length of time by leaving the tree therein, and when it is desired to remove the tree from the shoe, the dog 22 is raised and the lever 18 moved 100 backwardly and the pawl 21 raised and the tree may then be removed from the shoe, as will be readily understood.

The toe piece 14 may be of any desired length and it will be understood that my 105 improved shoe tree may be made of any preferred dimensions, and changes in and modifications of the construction herein described may be made, within the scope of the appended claims, without departing 110 from the spirit of my invention or sacrificing its advantages.

Having fully described my invention what I claim as new and desire to secure by Letters Patent is:—

1. A shoe-tree comprising a heel block and a toe block, a bar pivoted in the front face of the heel block and composed of separate parallel side members, a bar pivoted in the toe block and slidably connected with the bottom of the first named bar and provided in its top edge with ratchet teeth, a lever pivoted in the rear end portion of the bar that is pivoted in the heel block, a pawl connected with said lever and operating in connection with said ratchet teeth and adapted to force the toe block forwardly when the lever is swung forwardly, and means for holding said lever in its foremost position.
2. A shoe-tree comprising a heel block and a toe block, a bar pivoted in the front

face of the heel block and composed of parallel side members, a bar pivoted in the toe block and slidably connected with the first named bar and provided with ratchet teeth, a lever pivoted in the rear end portion of the bar that is pivoted in the heel block, a pawl connected with said lever and operating in connection with said ratchet teeth and adapted to force the toe block forwardly when the lever is swung forwardly, and means for holding said lever in its foremost position.

In testimony that I claim the foregoing as my invention I have signed my name in presence of the subscribing witnesses this 6th day of May 1912.

EDWARD J. KOBERT.
